US0D1086442S

(12) **United States Design Patent** (10) **Patent No.:** **US D1,086,442 S**
Sanders (45) **Date of Patent:** **** Jul. 29, 2025**

(54) **LOW PROFILED COMPACT RESPIRATORY FILTER AND INTERNAL FRAME ASSEMBLY**

(71) Applicant: **JSP Limited**, Minster Lovell (GB)

(72) Inventor: **Stephen Francis Sanders**, Minster Lovell (GB)

(**) Term: **15 Years**

(21) Appl. No.: **29/774,661**

(22) Filed: **Mar. 18, 2021**

Related U.S. Application Data

(62) Division of application No. 29/624,757, filed on Nov. 3, 2017, now Pat. No. Des. 955,551.

(57) **CLAIM**

The ornamental design for low profiled compact respiratory filter and internal frame assembly as shown and described.

DESCRIPTION

FIG. 1 is a perspective view of a base of my design;

FIG. 2 is a top perspective view of the design;

FIG. 3 is a bottom view of the design;

FIG. 4 is a top view of the design;

FIG. 5 is a right side view of the design;

FIG. 6 is a left side view of the design;

FIG. 7 is a front view of the design; and,

FIG. 8 is a rear view of the design.

1 Claim, 7 Drawing Sheets
